7 Claims. (Cl. 29—211)

ABSTRACT OF THE DISCLOSURE

Machine for assembling, for example, washers on a pin. The washers are fed by a reciprocating member, one by one, to a position coaxial with the pin. The pin is movable by the member between a washer engaging position and a rest position.

This invention relates to machines for handling components, such as assembling washers on a pin.

According to the invention, there is provided a machine for accepting components capable of being located about a receiving pin and locating such components about a receiving pin, comprising a carrier member movable between a first position adjacent a supply station providing a supply of such components in predetermined sequence and a second position adjacent a receiving pin, a first slot in said member opening towards said pin and also opening towards said supply station, a second slot in said member at right angles to said first slot and opening towards said pin so as to coincide with the pin or a projection thereof when said member is at the second position, lever means actuated as said member moves from the first to the second position to retract said pin from a rest position in which it would otherwise coincide with said second slot, and latch means operable to permit the pin to return to its rest position so as to lie within said second slot when said member reaches said second position; whereby a component inserted edgewise in said first slot is located about said pin and retained thereabout when said member is returned to said first position.

One embodiment of the invention will now be described, by way of example only, with reference to the accompanying drawings in which:

FIGURE 1 shows a side elevation;

FIGURE 2 shows a partial plan view; and

FIGURE 3 shows an end view, in the direction of the arrow in FIGURE 1, of the embodiment.

Referring to the drawing, the mechanism is assumed to be attached to a member 20 (which may be part of further machinery which co-operates with the mechanism). The mechanism comprises a sliding block 2 moved by a piston 22 (e.g. a pneumatic piston) between a first position (as shown) and a second position adjacent a receiving pin 8. The component-handling operation carried out by the mechanism is to transfer washers 28 one at a time from an inclined supply chute or track 1 to the pin 8.

The block 2 slides along a carriage way 6 on a base frame member 23 and a triangular-shaped lever 7, pivoted at 9, projects upwardly through an opening in the bottom of the carriage way in the path of a latch 5 carried by the block 2. The latch 5 is pivoted at 5a and is free to pivot upwardly in a clockwise direction, against the force of a return spring 5b, but is locked against anticlockwise movement beyond the position shown in FIGURE 1. The pin 8 is vertically slidable in a barrel 24 and is spring loaded to a rest position (as shown). The lower end 8a of the pin is engaged by a projection 7a of the lever 7 so

2

that pivoting of the lever causes the top end of the pin to retract from the rest position a short distance into the barrel.

The block 2 supports a carrier member in the form of an upper extension arm 25 at the end of which is a finger 26 hinged to the arm at 27. As best seen from FIGURE 2, the finger is spring-loaded, by a spring 10, towards the opening of a first slot 4 (FIGURE 1) in the end of the arm 25, this slot also opening towards and being aligned with the end of the component feeding chute 1 when the block 2 and arm 25 is in the first position shown. However, in this position the end of the finger 26 is engaged with a stop in the form of a projection 1a at the end of the chute so as to be held slightly spaced from the slot 4 opening. This permits a washer to be freely inserted edgewise from the chute into the slot 4, as shown at 28a, so that the washer aperture lies across a second slot 3 (FIGURE 2) in the end of the arm 25, the slot 3 being at right-angles to the slot 4.

In operation, with the block 2 in its first position the piston 22 is actuated to slide the block towards the pin 8. The depth of the first slot 4 is such that the washer 28a projects from the slot towards the finger 26 so that, as the finger leaves the chute projection 1a it closes on, and retains, the washer. The latch 5 then strikes the lever 7 which pivots so that the pin 8 is retracted. As the block 2 reaches the end of its travel, the arm 25 overlies the barrel 24 with the aperture of washer 28a aligned with the pin 8. Also, the trailing edge of latch 5 clears the lever 7 so that the pin 8 is freed to spring up through the washer aperture to its rest position. At the same time, a projecting stop 30 on the block 2 engages and pivots a lever 31 (normally sprung against a fixed stop 30a) which operates a valve 32 to reverse the piston 22. As the block 2 moves away from the pin, the washer and the pin are passed sideways out of the slots 3 and 4 and the finger 26 is deflected by the edge of the washer until it overrides the latter and springs back against the end of arm 25. The latch 5 pivots clockwise to override the lever 7 (now returned to the position shown) so that the latter is not moved on the return stroke.

As the block 2 reaches its first position, the finger 26 engages the chute projection 1a and a further washer moves into the slot 4. It will be understood that the chute opening is closed by the side face of arm 25, to retain the supply of washers 28, during movement of the arm towards and away from the pin 8.

The invention is not limited to the handling of washers but is applicable to the handling of numerous like components. For example, eyelets might be handled and, in such a case, the barrel 24 might be part of the anvil of an eyelet inserting press. Furthermore, it is envisaged that more than one component may be inserted at a time into the slot of the carrier member to be located in overlying relationship on the pin.

I claim:

1. A machine for assembling a pin and a component capable of being located about a receiving pin, comprising a carrier member movable between a first position adjacent a supply station providing a supply of such components in predetermined sequence and a second position adjacent a receiving pin, a first slot in said member opening towards said pin and also opening towards said supply station, a second slot in said member at right-angles to said first slot and opening towards said pin so as to coincide with the pin or a projection thereof when said member is at the second position, lever means actuated as said member moves from the first to the second position to retract said pin from a rest position in which it would otherwise coincide with said second slot, and latch means operable to permit the pin to return to its rest position so as to lie within said second slot when said

member reaches said second position; whereby a component inserted edgewise in said first slot is located about said pin and retained thereabout when said member is returned to said first position.

2. A machine as claimed in claim 1, wherein when said member is at the first position said first slot constitutes an extension of a supply chute at said supply station.

3. A machine as claimed in claim 2, wherein a slot-closing finger is hingedly mounted on said member and spring-loaded so as normally to extend across that opening of said first slot which is towards said pin, said finger being capable of hinging so as to override and release said receiving pin when said member is withdrawn from said second position.

4. A machine as claimed in claim 3, wherein the depth of the first slot in the direction towards the receiving pin is such in relation to the corresponding dimension of the component being handled that a component inserted in the slot will project from the slot; whereby the latch bears upon and retains a component during movement of said member towards said second position.

5. A machine as claimed in claim 4, wherein said finger is arranged to engage a stop at the supply station when

said member is at said first position so as to be held away from the first slot sufficiently to permit free insertion of a component therein.

6. A machine as claimed in claim 1, wherein said carrier member is slideable along a carriageway between said first and second positions, said latch means is carried by said member, and said lever means projects through an opening in said carriageway to lie in the path of said latch means and to be actuated thereby to retract said pin from its rest position.

7. A machine as claimed in claim 6, wherein said latch means is ineffective to actuate said lever means when said carrier member is returned to its first position.
